APPARATUS FOR AEROGRAVIMETRIC PROSPECTING

Carl A. Heiland, Denver, Colo.

Application July 8, 1946, Serial No. 681,907

4 Claims. (Cl. 73—382)

1

This invention relates to improvements in apparatus for locating potential oil bearing structures in the earth's geologic formations by the use of gravimetric devices lowered to the ground from certain types of aircraft. By this type of prospecting, the investigation of large areas may be carried on rapidly regardless of the character of the surface topography and the existence of gravitational anomalies may be detected in regions which would otherwise be inaccessible, such as swamps, jungles and the like.

It is well known to those versed in the art that the occurrence of oil deposits in the earth is controlled by the existence of suitable traps in subsurface geologic structures. These traps include faults, anticlines, domes and salt plugs. In all of these structures oil bearing strata, which were laid down originally in horizontal positions, have been uplifted or tilted, making possible a density separation of gas and oil and a separation of the oil from the so-called connate waters contained in the oil beds. Oil deposits may therefore be located indirectly by prospecting for the types of geologic structures just mentioned.

Experience has shown that oil bearing structures, particularly those associated with uplifts, generally produce gravitational anomalies. Due to the fact that in the core of an uplift, the older and usually denser strata are brought closer to the surface, the presence of anticlines and domes generally will be indicated by gravitational highs, that is, by local increases in the force of gravity. An exception to this rule are salt plugs which, because of the fact that salt is lighter than the surrounding sediments, are usually indicated by gravitational lows.

Gravimetric prospecting for oil bearing structures has in the past been mostly confined to land areas and the like which are generally accessible to vehicle transport. Another complication which has arisen in the past in connection with land surveys is that, on account of the fact gravity is affected perceptibly by elevation, it has been necessary to conduct accurate topographic surveys wherever gravity measurements are made.

The present invention overcomes the above-mentioned difficulties by providing a new apparatus for prospecting according to which gravimetric surveys of inaccessible areas may be made through the use of aircraft for carrying a gravimeter to such areas, coupled with means for determining accurately the elevations of the points at which measurements are made. More specifically, these objects are accomplished by

lowering a gravimeter to the desired places on the earth's surface from aircraft such as a helicopter or a dirigible balloon, either of which is capable of slow movement and of hovering over a given point, making gravity measurements at those places, and determining by optical or radio triangulation methods the relative elevations of the places where gravity measurements are made. Other objects relate to various features of the apparatus which will appear more fully hereinafter.

The nature of the invention will be understood from the following specification taken with the accompanying drawings in which one embodiment of the improved apparatus and certain modifications thereof are disclosed in connection with the disclosure of the improved method.

In the drawings,

Figure 1 is a somewhat diagrammatic elevational view and partial perspective view of one form of the improved apparatus of the present invention in which a gravimetric measuring device is illustrated as having been lowered to the ground from a helicopter;

Fig. 2 shows an enlarged vertical section through the principal part of the gravity measuring device illustrated in Fig. 1;

Fig. 3 shows a horizontal section on the line 3—3 of Fig. 2;

Fig. 4 shows a horizontal section on the line 4—4 of Fig. 2;

Fig. 5 shows an enlarged detail of the circuit connections of a portion of the apparatus illustrated in Fig. 2;

Fig. 6 illustrates in perspective an optical triangulation method which may be employed to determine the elevation of the gravimeter station; and

Figs. 7 and 8 illustrate somewhat diagrammatically a radio location method which may be used to find the elevation of the gravimeter station.

The aircraft used in this work may be a helicopter plane or a dirigible balloon of the type commonly known as a "blimp" by which the gravimetric instrument is carried to the desired location and from which this instrument is then lowered to the ground by means of a cable. In Fig. 1 a helicopter 10 is shown hovering in a substantially stationary position over a place on the surface of the earth 11 to which a gravimetric measuring device 12, suspended from a skeleton-like tripod or frame 14, has been lowered from the airplane by means of a cable 15. The frame 14 and the measuring instrument 12,

suspended therein by a wire or the like 16, are of sufficient weight to cause the spikes 15^a carried by the frame to enter the earth and hold the frame in a fixed position. The cable 15 is payed out from a winch on the helicopter or other aircraft employed and the gravimeter and its tripod or frame serve as an anchor to hold the aircraft temporarily above the spot where the measurements are to be made.

Although the gravimetric measuring instrument 12 levels itself with a substantial degree of accuracy by virtue of its suspension by the wire 16, means are provided, as shown in Figs. 2, 3 and 4, for more accurately leveling the measuring mechanism inside of the casing in which it is housed and means are also provided for obtaining a dial reading of the gravity measurement while the instrument is on the ground so that, when the instrument is subsequently hoisted back onto the aircraft, that reading may be taken off by the observer. There is provided within the outer casing 17, to which the wire 16 is attached, a heavy supporting plate 18 from which the remainder of the measuring instrument is supported by four leveling screws 19 having threaded engagements with nuts 20 secured in the plate 18. The lower ends of the screws 19 are mounted in ball bearing units 21 which are mounted on the top wall 22a of a frame 22 on which the measuring instruments proper are located. The screws 19 are located opposite to each other in right-angularly disposed pairs so that by their adjustment the frame 22 may be tilted in any desired fashion to effect a proper and accurate leveling of the gravity measuring mechanism.

For the purpose of turning the screws 19 they are each provided with a relatively fixed bevel gear 24 which meshes with a bevel pinion 25 fixed on a shaft 26 of one of the radially extending pairs of shafts 26 and 27, each of which is journaled in a bearing 28 carried by the cross-shaped top bracket 22a of the frame. The pair of aligning shafts 26 are connected by universal joints 29 with an intermediate shaft 30 journaled in a block 31 carried by the top bracket 22a and having fixed thereon a worm wheel 32. This worm wheel meshes with a worm 35 fixed upon the upper end of a shaft 36 which is driven in the manner hereinafter described to effect the tilting or leveling of the frame 22 and its contents in the plane of the screws 19 to which the shafts 26 are connected. The shafts 27, which are located in a plane at right angles to the plane containing the shafts 26, have fixed thereon a worm wheel 38 arranged to mesh with a worm 39 fixed on the upper end of a shaft 40 adapted to be driven in the manner hereinafter described. The operation of the shaft 40 will thus tilt the frame 22 and its contents in the plane of the adjusting screws 19 which are connected to the shafts 27.

The means for operating the shafts 36 and 40 and the means for measuring the force of gravity are carried by the frame 22 which comprises, in addition to the top bracket 22a, a bottom bracket 22b, four upright legs 22c which connect the outer edges of the brackets 22a and 22b and which are in turn connected by four radiating intermediate arms 22d united with each other at their inner ends, forming a hub 22e. This hub is supported from the bottom bracket 22b by a center post 22f.

Beneath each of two right-angularly disposed arms 22d of the frame 22 there is mounted a horizontal pendulum 41 as shown in Figs. 2 and

4. Each pendulum comprises a vertical shaft 41a having cone-shaped extremities, the lower one of which has a bearing in a block 42 mounted in the bottom plate 22b while the upper extremity 5 has a bearing in a recess in the under side of a bearing block 44 mounted in the hub portion 22e and adjustable by means of a screw 44a for the purpose of regulating the position of the pendulum. Each pendulum is provided at its outer end with a bob 41b from the outer extremity of which a damping vane 45 of copper or the like extends between the poles of a permanent magnet 46 by which the swinging movements of the pendulum are damped.

The upper portion of the shaft 41a of each horizontal pendulum has mounted thereon a mirror 47 adapted to receive a narrow beam of light 48 from a Lucite tube 49 extending from an alternating current or interrupted current light source 50. The beam of light 48 received by each mirror 47 is reflected along the path 51 to a V-shaped prism 52 (see Fig. 5), mounted on one of the legs 22c, which splits the beam and directs the light to two photo-electric cells 54 and 55 20 mounted at opposite sides of the prism on the adjacent leg 22c. The double-faced prism and the two photo-electric cells are so arranged and adjusted that when the reflected light beam strikes the prism evenly so that the same amount 25 of light strikes each photo-electric cell, the instrument is exactly level in a plane at right angles to the arm 22d beneath which the associated horizontal pendulum 41 is mounted. The circuit connections of each pair of photo-electric cells 54 and 55 in relation to the light beam and the adjacent prism are shown in Fig. 5 where the terminals of the photo-electric cells are shown connected to an amplifier 57 which operates a servo-motor 58 or 59. One such amplifier and associated servo-motor 59 are connected to drive the vertical shaft 36 which operates one pair of adjusting screws 19 and the other servo-motor 58 is connected to drive the vertical shaft 40 by which the other pair of adjusting screws 19 are 30 operated. In this way a movement of the measuring instrument in either of two right-angularly disposed directions out of a true level position will cause a swinging of one of the horizontal pendulums 41 out of its centered position and a resulting actuation of the related photo-electric cells 54 and 55 to cause one of the servo-motors 58 or 59 to operate two of the adjusting screws and restore the level condition in that direction.

Under another of the arms 22d of the frame 22 35 there is pivotally mounted a vertically swinging pendulum 60 which is provided at its inner end with a pointed extremity 60a adapted to rock in a recess formed in a web 22g of the frame which extends vertically between the adjacent arm 22d and the bottom plate 22b. This pendulum has a bob 60b at its free end and a coil spring 61 extends between a point on the pendulum adjacent the bob to the upper end of the web 22g, making an angle of approximately forty-five degrees with the longitudinal axis of the pendulum. At its inner end the pendulum 60 carries an up-standing arm 60c on which is mounted a mirror 62 adapted to receive a small beam of light 64 from a Lucite tube 65 leading from the previously described light source 50. The beam of light 64 is reflected from the mirror 62 along a line 66 to a double prism 67 mounted on one of the legs 22c with its apex extending horizontally. Two photo-electric cells 68 and 69 are mounted on opposite 40 sides of the prism 67, one above and one below,

and when the pendulum 60 is in the zero or reference position, which may be termed its minimum level sensitivity position, the beam of light is divided into equal parts by the prism 67 and equal amounts of light pass to the photo-electric cells 68 and 69.

After the gravity measuring instrument has been leveled by the action of the adjusting screws 19 in the manner previously described, the pendulum 60 will usually be out of the zero or reference position just referred to and the major portion of the light in the beam will pass to one or the other of the photo-electric cells 68 or 69. These cells are connected in circuit with an amplifier and a servo-motor 70, shown in Fig. 4, in the manner previously described in connection with Fig. 5, so that when this unbalanced condition exists between the cells 68 and 69, the connected amplifier causes the servo-motor 70 to operate and thereby actuate a pinion 71 through a mechanical connection 72, illustrated diagrammatically in Fig. 4, and this pinion drives the meshing gear 74 having a threaded engagement with a micrometer screw 75. This micrometer screw thus moves endwise under the influence of the servo-motor 70 and through suitable mechanism, illustrated for convenience as a spring 76, the pendulum 60 is moved back to its zero or reference position. The extent of this movement is an indication of the force of gravity at the place where the instrument is located and may be recorded on a dial or counter. For example, the micrometer screw 75 may be connected to a flexible shaft 77 which will actuate a counter 78 located on the outside of the housing 17. By the use of this mechanism the gravity measurement at each station will require only a short period of time, whereupon the instrument 12 and its frame or tripod 14 are hoisted back onto the aircraft 10 and the dial position is noted and recorded.

This reading of the relative value of gravity at a station would be without value unless means were provided for determining accurately the elevation of the station. It is assumed that surveyors cannot get to the station and other means must therefore be employed to find the station elevation. One method, which is accurate, although somewhat complicated, is illustrated in Fig. 6. According to that plan, the position of the aircraft in space is determined at all times by recording telescopes T1, T2 and T3 set up at three ground stations which are removed from the inaccessible location where the gravity measurement is taken. Two of these telescopes T1 and T2 are sufficient but the third one is convenient when unfavorable angles are encountered. Through the use of these telescopes there are obtained, at any instant, the values of the angles a_1 , a_2 and a_3 , thus fixing the horizontal position of the aircraft 10 with respect to the three stations, and also the angles b_1 , b_2 and b_3 which fix the vertical elevation h of the aircraft above a plane containing the three stations. By recording the times on the ground when these simultaneous observations are made and by making concurrent time determinations in the airplane 10, the position of the airplane in space, particularly its vertical elevation above the ground, is determined. To arrive at the elevation of the station where the instrument 12 is located when a measurement is taken, it is merely necessary for the observer to read graduations provided on the hoisting cable 15 to determine directly the elevation of the aircraft above that measurement station.

A less accurate but more rapid method of determining the elevation is shown in Figs. 7 and 8, where the airplane 10 is equipped with two short wave radio transmitters Tr which trigger two (or more) radio ground stations with receivers R1 and R2 and transmitters Tr1 and Tr2 which are spaced apart a distance D. The impulses transmitted by the two ground stations Tr1 and Tr2 are received in the plane by the receivers R. For purposes of identification and ease of operation the frequencies of the two channels are different. The distance of the aircraft from the two stations R1 and R2 may be indicated by the periods of time t_1 and t_2 required for the impulses to travel from the aircraft to the receivers R1 and R2 and return, which may be indicated by dials S1 and S2 in a conventional manner. The location of the airplane with respect to the two ground stations is thereby established approximately since t_1 and t_2 are proportional to the horizontal distances d_1 and d_2 , respectively. The absolute elevation of the aircraft above sea level is then determined by using a microbarometer; and the elevation h_1 of the plane above the measuring station M may be determined by using the hoisting cable as a measuring tape.

Through the determination of the relative elevations of the measuring stations and the measurement of the force of gravity at those stations which may be distributed as desired over a large area, some parts or all of which may be inaccessible to land transport, it is possible to obtain an indication of the presence or absence of potential oil bearing structures in the underlying geologic formations.

Although one embodiment of the improved gravimetric apparatus has been shown and described and modifications of certain portions thereof, by way of illustration, it will be understood that the apparatus may take various forms within the scope of the appended claims.

I claim:

1. In apparatus for gravimetric surveying from aircraft, a gravity measuring device adapted to be lowered to the ground from said aircraft and comprising a ground engaging frame having a supporting plate, a gravity measuring instrument suspended from said plate by leveling means, and means comprising two horizontal pendulums normally located in right-angularly disposed planes for automatically operating said leveling means to level said instrument in two directions.

2. In apparatus for gravimetric surveying from aircraft, a gravity measuring device adapted to be lowered to the ground and including a ground engaging frame, a gravity measuring instrument suspended from said frame by leveling means, and means comprising servo-mechanism actuated by two horizontal pendulums normally located in right angularly disposed planes for automatically operating said leveling means to level said instrument in two directions.

3. In apparatus for gravimetric surveying from aircraft, a gravity measuring device adapted to be lowered to the ground and including a ground engaging frame, a gravity measuring instrument suspended from said frame by leveling means, and means comprising servo-mechanism actuated by two horizontal pendulums normally located in right angularly disposed planes for automatically operating said leveling means to level said instrument in two directions.

directions, said gravity measuring instrument comprising means for automatically recording the gravity measurement while said device is supported on the ground.

4. In apparatus for gravimetric surveying from aircraft, a gravity measuring device adapted to be lowered to the ground and comprising a ground engaging frame, and a gravity measuring instrument suspended from said frame by automatic leveling means, said instrument comprising a vertically swinging pendulum for causing a light beam deflection and photoelectrically actuated means for correcting the beam deflection and recording the gravity measurement indicated thereby within the instrument while said instrument is so supported on the ground.
